BABY BATHTUB

J. L. Johnson, Jr., P.O. Box 4, Goldsmith, Tex.

Filed Aug. 24, 1959, Ser. No. 57,260

Term of patent 14 years

(Cl. D4—4)

Fig. 1 is a front perspective view of a baby bathtub embodying my new design;

Fig. 2 is a longitudinal sectional view thereof, taken on line 2—2 of Fig. 1; and

Fig. 3 is a transverse sectional view thereof, taken on line 3—3 of Fig. 1.

I claim:

The ornamental design for a baby bathtub, as shown.
